UNITED STATES PATENT OFFICE.

THOMAS E. CAIN, OF LOMBARD, MARYLAND.

COMBINATION BURGLAR-ALARM AND WINDOW-SASH.

No. 900,146.

Specification of Letters Patent.

Patented Oct. 6, 1908.

Application filed April 24, 1906. Serial No. 313,457.

To all whom it may concern:

Be it known that I, THOMAS E. CAIN, a citizen of the United States, residing at Lombard, in the county of Cecil and State 5 of Maryland, have invented a new and useful Improvement in a Combination Burglar-Alarm and Window-Sash, of which the following is a specification.

This invention is a combined window stop 10 or fastener and burglar alarm, the object of the invention being to provide a cheap simple and efficient device which can be attached to the window sash and frame and by means of which the window can be securely 15 locked in a closed or intermediate position and another object of the invention is to provide in connection with the locking mechanism, an alarm which will sound when the window is either raised or lowered, there- 20 by providing an efficient form of burglar alarm.

With these objects in view, my invention consists essentially in the employment of a rack bar which is arranged upon the side 25 rail of the window sash and which is adapted to engage a pinion mounted upon the window frame which pinion is adapted to be engaged by a pawl for the purpose of locking the window in a raised position, and the 30 invention also consists in the employment of a bell provided with a lever or handle for operating the same, which lever or handle is acted upon by a movable bail connected to the pinion so that in case the window is 35 raised or lowered, the bail pulling upon the lever will cause the bell to ring and thereby give the alarm.

The invention consists also in certain details of construction and novelties of combination all of which will be fully described hereinafter, and pointed out in the claims.

In the drawings forming a part of this specification: Figure 1 is a perspective view showing the practical application of my invention. Fig. 2 is a detail sectional elevation. Fig. 3 is a sectional plan view. Fig. 4 is a detail face view. Fig. 5 is a detail perspective view of the pinion carrying the crank pin. Fig. 6 is a detail perspective 50 view of the operating bail.

In these drawings A indicates the side rail of the window sash, and B the window frame, said parts being of the usual or ordi-

nary construction and secured to the side rail of the sash is a rack bar C which is adapted 55 to be engaged by a pinion D mounted upon the window frame, and a pawl E pivoted also to the window frame permits the pinion to rotate in one direction but prevents the said pinion rotating in the opposite direc- 60 tion. By this arrangement the window can be raised and held locked in a completely raised or intermediate position. Any suitable form of catch or lock F may be arranged upon the window sill for the purpose 65 of engaging the bottom tooth of the rack bar and thereby securely fasten the window in a closed position.

G indicates a bell having a handle or lever H, projecting therefrom, and by means of 70 which the said bell is sounded and for the purpose of operating this handle or lever when the window is raised or lowered, I employ a bail I, essentially rectangular in shape, the bottom member of which is adapt- 75 ed to fit beneath the handle or lever H and at its upper end this bail is constructed with an eye I', which fits over a crank pin K, carried by the pinion D, so that a new movement of the window either up or down, will 80 cause the pinion to rotate and this rotation of the pinion will work the bail up and down and cause it to pull upon the handle or lever H, and in order to hold this bail in this position at all times, I employ a guide eye L, 85 which is secured to the window frame and through which the free end of the bail works as shown clearly in Fig. 4.

The pawl E can be thrown off whenever it is desired to lower the window and the 90 bail is so constructed and arranged that if desired to disconnect it during the day, so as to avoid sounding the alarm, it can be quickly and easily accomplished by simply removing the eye from the crank pin of the 95 pinion.

It will thus be seen that I provide an exceedingly cheap, simple and efficient form of combination window lock or fastener and burglar alarm.

Having thus fully described my invention, what I claim as new and desire to secure by Letters Patent, is:—

In a device of the kind described, the combination with the rack bar, pinion and pawl, 105 of a bell provided with a lever or handle, a.

crank pin, carried by the pinion, an essentially rectangular shaped bail having an eye at its upper end adapted to fit upon the crank pin, the lower member of the bail fitting beneath the handle or lever and an eye through which the free end of the bail is adapted to move, all of said parts being ar-

ranged and adapted to operate substantially as shown and described.

THOMAS E. CAIN.
